MERCURY SWITCH AND THE LIKE

Filed July 2, 1930

Inventor:
Siegfried Held
By Leo A. Baumgarten
Atty.

UNITED STATES PATENT OFFICE

SIEGFRIED HEED, OF CHICAGO, ILLINOIS

MERCURY SWITCH AND THE LIKE

Application filed July 2, 1930. Serial No. 465,384.

This invention has to do with improvements in mercury switches and the like. The features herein disclosed have reference particularly to improvements in mercury switches of what may be designated as a double pole, double throw construction—that is, a construction in which the switch is provided with two poles and can be thrown into either of two positions.

One of the objects of the invention is to provide a switch of very simple form and construction embodying the features just above referred to, and a construction in which the parts are very compactly arranged and are so located and related to each other that the necessary relationship is produced with a minimum number of parts and contacts.

Another feature of the invention relates to the provision of a construction such that the operations of actually opening and closing the circuit are performed by the mercury bath itself and by establishing or discontinuing contact between two portions of said bath, as distinguished from those arrangements in which the making and breaking of the circuit is performed by establishing and discontinuing connection between a contact and the mercury bath.

In connection with the foregoing, it is a further object of the invention to so relate the parts that the above results can be secured in a switch construction of the double pole type.

A further feature relates to the provision of an arrangement such that the operations of actually making and breaking the circuit are performed in the position of a bridge piece or "weir"; and a further object is to accomplish this result in switches of the double pole type.

Other objects and uses of the invention will appear from a detailed description of the same which consists in the features of construction and combinations of parts hereinafter described and claimed.

In the drawing:

Figure 1 shows a horizontal section through a switch construction embodying the features of the present invention. It may also be considered as a section substan-

tially on the lines 1—1 of Figures 2 and 3, looking in the direction of the arrows;

Figure 2 shows a vertical section substantially on the line 2—2 of Figure 1, looking in the direction of the arrows, the switch being tilted towards the left so that the connections are made at the left hand contacts and are broken at the right hand contacts;

Figure 3 shows a view similar to that of Figure 2, being taken on the line 3—3 of Figure 1, looking in the direction of the arrows, the switch being tilted towards the right so that the connection is established at the right hand contacts and is broken at the left hand contacts;

Figure 4 shows a cross section on the line 4—4 of Figure 1, looking in the direction of the arrows; and

Figure 5 shows a cross section on the line 5—5 of Figure 1, looking in the direction of the arrows.

The switch construction illustrated includes a body member 6, the central portion of which is of relatively narrow size which is enlarged vertically. Said body member includes a pair of longitudinally extending passages or compartments 7 and 8 which are relatively thin and deep. These compartments are separated by the partition 9 which reaches the full height of the body member 6.

Each end of the device is enlarged horizontally as best shown in Figure 1, so as to provide the supplemental contact chambers 10 and 11 at one end, and 12 and 13 at the other end. These contact chambers are preferably of the full height of the body member.

Furthermore, the end portions of the device are preferably brought into circular form so as to receive the enclosing caps 14 and 15; and preferably the disk washers 16 and 17 are set between these caps and the end portions of the body member so as to establish liquid-tight connections.

The compartments 10, 11, 12, and 13 are preferably set-off from the adjacent end portions of the compartments 7 and 8 by means of the partitions 18, 19, 20, and 21. The lower portions of these partitions extend the full length of the body member 6 and into

close engagement with the disk washers 16 and 17 as best shown in Figures 2 and 3. The upper portions of said partitions 18, 19, 20, and 21 are, however, cut high, as shown in the different figures so as to establish the openings 22, 23, 24, and 25, which establish lateral communication between the end portions of the compartments 7 and 8 and the adjacent compartments 10, 11, 12, and 13.

10 Central contact pins 26 and 27 reach downwardly in the central portions of the compartments 7 and 8. Other contact pins 28, 29, 30, and 31, reach downwardly in the respective end compartments 10, 11, 12, and 13, preferably behind the respective lateral openings 22, 23, 24, and 25, and adjacent to the positions of the partitions 18, 19, 20, and 21.

15 All of the contact pins 26, 27, 28, 29, 30 and 31, reach close to the floor of the body member 6.

20 The body member 6 is made of suitable insulating material, preferably bakelite or other condensation product which can be moulded; and the end caps 14 and 15 are 25 preferably of iron or other metal which is not subject to corrosion or disintegration by the action of mercury or the like.

25 A body of metallic mercury is placed in each side of the device, the two bodies of mercury being at all times separated and insulated from each other by means of the central partition 9. Upon tilting the device in the position of Figure 2, the respective bodies of mercury will run over to the left hand end and will establish contact between the central contact pins 26 and 27 and the end contact pins 28 and 29 respectively. Upon tilting the device over into the position of Figure 3, the mercury will flow towards the right hand end. As the level of the mercury at the left hand end thus falls, the two bodies of mercury will break over the respective partitions 18 and 19, thereby breaking contact between the pins 26 and 27, and 28 and 29, respectively. At the same time the flow of mercury towards the right hand end will cause the level to rise at that end sufficiently to cause the respective bodies of mercury to flow past the respective partitions 20 and 21 and thus establish connection between the pins 26 and 27, and 30 and 31, respectively.

30 Preferably the parts are so proportioned and the amount of mercury present is such that the circuit is in each instance broken at the left hand end before it is established at the right hand end. In this way the possibility of improper establishment of connections is avoided. At the same time, it is preferred that the bodies of mercury maintain connection at all times with the central pins 26 and 27, respectively, as indicated in Figures 2 and 3. Furthermore, the pins 28, 29, 30, and 31, will at all times maintain connection with the bodies of mercury trapped in the respective compartments 10, 11, 12 and

13, so that assurance is had that the making and breaking of the different circuits is accomplished by connection and breaking of bodies of mercury over the partitions.

35 If desired, baffles or partitions such as 32 70 may be formed on the body member so as to prevent improper connection between the upwardly projecting ends of the respective pins. Also, if desired, the interior of the body member may be filled with suitable insulating and arc extinguishing liquid above the respective bodies of mercury.

40 While I have herein shown and described only a single embodiment of the features of my present invention, still I do not intend to limit myself thereto except as I may do so in the claims.

I claim:

45 1. As a new article of manufacture, a switch comprising a body member formed of insulating material and having a pair of longitudinally extending compartments reaching the full height of the body member throughout their length, a vertical partition separating said compartments and insulating them from each other, a lateral chamber adjacent to each end of each compartment, there being an opening connecting each chamber aforesaid with the end portion of the adjacent compartment, said openings being located above the floors of the respective chambers and compartments, a pair of central contacts in the lower central portions of the compartments, a contact in each of said lateral chambers, a body of metallic mercury or the like within each compartment and the adjoining chambers, and suitable insulating and arc extinguishing liquid within each compartment and the adjoining chambers above the level of the metallic mercury therein, the arrangement being such that when the device is tilted in one direction the bodies of metallic mercury flow to one end thereof and fill the chambers and that end of the compartments to a level to establish electrical connections from the compartments through the respective lateral openings into the respective adjoining chambers and thereby establish electrical connections from the central contacts to the contacts within the end chambers aforesaid, and whereby when the device is tilted in the other direction the bodies of metallic mercury flow to the other ends of the respective compartments and break over the openings establishing communication at the chambers of the first mentioned end and establish connection through the openings at the second mentioned end, substantially as described.

50 2. In a device of the class described, the combination of a body member of insulating material having a pair of longitudinally extending compartments separated and insulated from each other by a vertical partition, an end chamber laterally adjacent to each end of each of said compartments; there

being openings between the ends of the compartments and the laterally adjacent chambers, said openings being located above the floors of the compartments and chambers
 5 and further from the center of the device than the inner ends of the respective chambers, to thereby establish weirs between the ends of the compartments and the adjacent chambers, contact members in the central
 10 portions of the compartments, contact members in the end chambers located closer to the central portion of the device than the openings aforesaid, and bodies of metallic mercury or the like within the compartments
 15 and the end chambers, substantially as described.

3. In a device of the class described, the combination of a body member of insulating material having a pair of longitudinally extending compartments separated and insulated from each other by a vertical partition, an end chamber laterally adjacent to each end of each of said compartments, there being openings between the ends of the compartments and the laterally adjacent chambers, said openings being located above the floors of the compartments and chambers and further from the center of the device than the inner ends of the respective chambers,
 20 to thereby establish weirs between the ends of the compartments and the adjacent chambers, contact members in the central portions of the compartments, contact members in the end chambers, and bodies of metallic mercury or the like within the compartments and the end chambers, substantially as described.

4. In a device of the class described, the combination of a body member of insulating material having a pair of longitudinally extending compartments, a vertical partition separating said compartments from each other, lateral chambers adjacent to the end portions of said compartments, there being openings between the end portions of the compartments and the adjacent chambers, contact members in the central portions of the compartments, contact members in the chambers, a body of metallic mercury or the like within each compartment and the end chambers therefor and suitable insulating and arc extinguishing liquid within each compartment and the end chambers thereof above the metallic mercury therein, substantially as described.

5. In a device of the class described, the combination of a body member of insulating material having a pair of longitudinally extending compartments, a vertical partition separating said compartments from each other, lateral chambers adjacent to the end portions of said compartments, there being openings between the end portions of the compartments and the adjacent chambers, contact members in the central portions of

the compartments, contact members in the chambers, and a body of metallic mercury or the like within each compartment and the end chamber therefor, substantially as described.

6. In a device of the class described, the combination of a body member of insulating material, a longitudinally extending compartment therein, a chamber laterally adjacent to each end of said compartment, there being an opening between the upper outer corner of the compartment at each end and the adjacent end chamber, a central contact member in the central portion of the compartment, an end contact member in each chamber located closer to the center of the device than the adjacent opening aforesaid, and a body of metallic mercury or the like within the compartment and the end chambers, substantially as described.

7. In a device of the class described, the combination of a body member of insulating material, a longitudinally extending compartment therein, a chamber laterally adjacent to each end of said compartment, there being an opening between the upper outer corner of the compartment at each end and the adjacent end chamber, a central contact member in the central portion of the compartment, an end contact member in each chamber, and a body of metallic mercury or the like within the compartment and the end chambers, substantially as described.
